UNITED STATES PATENT OFFICE

ROBERT DAVIDSON BELL, OF DUNDEE, ANGUS, SCOTLAND

APPARATUS FOR USE IN ELECTRIC SPOT-WELDING

Application filed October 14, 1932, Serial No. 637,828, and in Great Britain October 16, 1931.

This invention relates to apparatus for use in electric spot-welding and has for an object the provision of a manually operable device suitable for use in dentistry, watch and clock making, instrument making and other arts whereby metal articles and particularly but not necessarily small articles and more specifically those composed of stainless steel, may be electrically spot-welded. The apparatus may be employed without the use of a transformer, interrupter and switch if a battery forms the source of electric supply.

Briefly stated the present invention comprises electric spot welding apparatus of the character described comprising a manually movable rod mounted so that it is restrained to a predetermined path and provided with a pair of contacts each adapted to co-operate with a stationary contact electrically connected to a terminal of a battery or other electric supply and one of said stationary contacts forming the rest for the work to be spot welded and the other forming the fulcrum about which the rod turns.

My invention is shown by way of example in the accompanying drawings in which:—

Figure 1 shows a perspective view of a spot welding machine according to the present invention.

Figure 2 shows a side view.

Figure 3 shows a plan view.

Figure 4 shows an end view with the handle removed for the sake of clearness and

Figure 5 shows an enlarged sectional detail view on the line V—V of Figure 2 of the tail view on the line V—V of Figure 2 of the pivotal connection between the rod frame and the plate on which it is mounted.

In the machine shown in the drawings the rod 1 is manually operated by the handle 2 and is adjustably mounted in the cross head 3 pivotally mounted at the free extremities of the toggle arms 4 which are pivotally mounted on the cross member 5 attached by a piece of insulating material 24 to the metal plate 6 which in turn is mounted on the insulated base 7, which forms the top cover plate of the battery 8. The position of the rod 1 in the cross head 3 may be adjusted as desired and is locked in set position by the stud 21. The metal plate 6 is provided with

openings 9 in register with the terminals 10 of the battery (or other source of supply if not obtained from a battery) and according to the voltage required is designed to be connected with one or other of said terminals by means of the plug 11. This plate 6 is provided with a fixed contact 12 adapted to make connection with the curved contact end of the rod 1 when the rod is in the position shown in the drawings.

The terminal 13 of the battery has mounted thereon an angle arm 14 shown in dotted lines in Figures 2, 3 and 4. This arm carries a contact 15 which projects through an opening 17 in the insulated cover plate 7. The height of this contact may be increased as shown in the drawings by the additional contact piece 18. It should be understood that the contact piece 18 is not necessarily shaped as shown in the drawings but, may have a blunt or a sharp point. It may be bent or moulded into suitable shape to accommodate the work being done. It is tapered and fits into a socket in 15 and is interchangeable with other terminals designed for particular work. The fixed contact formed by the contact members, 15, 18 is adapted to form a rest or support for the work to be spotwelded. The point of the adjustable contact 19 mounted on the rod 1, is adapted to coact with the fixed contact members 15, 18 as shown in Figures 1 and 2 of the drawings. The position of the contact 19 on the rod 1 may be altered as required and the contact locked in set position by the stud 22.

In use the work to be spot-welded is placed above and rests upon the point of the stationary contact member 18 and the rod 1 is manipulated so that its curved end rests on the stationary contact 12 with its other adjustable contact 19 vertically or axially above the stationary contact member 18 on which the work is resting. The rod is now moved so that the contact 19 above the work approaches the work, the other pair of contacts comprised of its curved end and the contact 12 forming a fulcrum. As soon as the contact 19 touches the work the spot-weld is formed and immediately thereafter the operator moves the rod further so that the con-

nection between the curved end of the rod and the contact 12 forming the fulcrum is broken, the rod being restrained to move in a direction to break the connection between said 5 fulcrum contacts as soon as the spot-weld is formed.

The metal plate 6 is provided with an insulated stud 23 in line with the contact 12, upon 10 which the curved contact end of the rod is adapted to rest when the apparatus is out of use to prevent any chance of shorting between the toggle arms 4 and the metal plate 6. As shown in Figure 5 I prefer to provide 15 a spring 20 in the pivotal connection between the arms of the toggle frame 4, thus providing spring means tending to lift the contact 19 off the work to be spot welded, against which the handle is pressed down at the moment of welding.

20 What I claim is:—

1. Electric spot welding apparatus comprising a base, a manually movable rod mounted on said base, means for restraining the movement of said rod to a predetermined 25 path and a pair of contacts on said rod respectively adapted to co-operate with a pair of fixed contacts on said base connected to the terminals of an electric supply and one of said fixed contacts forming the rest for the 30 work to be spotwelded and the other forming the fulcrum upon which said rod turns during its movement to the spot welding position.

2. Electric spot welding apparatus comprising a base, a frame hinged to said base, a cross head hinged to the free extremity of said frame, a manually movable rod mounted intermediate of its ends in said cross head and adapted to be slidingly adjusted therein in 40 relation to the frame and a pair of contacts on said rod respectively adapted to co-operate with a pair of fixed contacts on said base respectively connected to the terminals of the electric supply and one of said fixed contacts 45 forming the rest for the work to be spotwelded and the other forming the fulcrum upon which said rod turns during its movement to the spot welding position.

3. Electric spot welding apparatus comprising an insulated base, a metal plate mounted on said base provided with openings therein in register with alternative terminals of one polarity of the electric supply, a plug adapted to connect said metal plate with one or the other of said terminals according to the voltage required, a fixed contact on said plate, a manually movable rod mounted on said metal plate, means for restraining the movement of said rod to a 50 predetermined path and a pair of contacts on said rod respectively adapted to co-operate with the fixed contact on said plate and a fixed contact on said base connected to the terminal of the other polarity of the electric supply and one of said fixed contacts forming 55

the rest for the work to be spotwelded and the other forming the fulcrum upon which said rod turns during its movement to the spot welding position.

4. Electric spot welding apparatus comprising an insulated base, a metal plate mounted on said base provided with openings therein in register with alternative terminals of one polarity of the electric supply, a plug adapted to connect said metal plate with one or other of said terminals according to the voltage required, a fixed contact on said plate, a frame hinged to said plate, a cross head hinged to the free extremity of said frame, a manually movable rod mounted intermediate of its ends in said cross head and adapted to be slidingly adjusted therein in relation to the frame and a pair of contacts on said rod respectively adapted to co-operate with the fixed contact on said plate and a fixed contact on said base connected to the terminal of the other polarity of the electric supply and one of said fixed contacts forming the rest for the work to be spotwelded and the other forming the fulcrum upon which said rod turns during its movement to the spot welding position.

5. Electric spot welding apparatus comprising a base, a toggle lever system mounted on said base, a manually movable rod mounted at the free end of said toggle lever system and a pair of contacts on said rod respectively adapted to co-operate with a pair of fixed contacts on said base connected to the terminals of an electric supply and one of said fixed contacts forming the rest for the work to be spotwelded and the other forming the fulcrum upon which said rod turns during its movement to the spot welding position.

6. Electric spot welding apparatus, comprising an insulated base, a metal plate mounted on said base provided with openings therein in register with alternative terminals of one polarity of the electric supply, a plug adapted to connect said metal plate with one or other of said terminals according to the voltage required, a fixed contact on said plate, a toggle lever system mounted on said plate, a cross head pivoted at the free end of said toggle lever system, a manually movable rod mounted intermediate of its ends in said cross head and adapted to be slidingly adjusted therein in relation to the toggle lever system and a pair of contacts on said rod respectively adapted to co-operate with the fixed contact on said plate and a fixed contact on said base connected to the terminal of the other polarity of the electric supply and one of said fixed contacts forming the rest for the work to be spotwelded and the other forming the fulcrum upon which said rod turns.

7. Electric spot welding apparatus com-

prising a base, a manually movable rod mounted on said base intermediate of its ends with a handle at one end and a downwardly curved free end, means for restraining the movement of said rod to a predetermined path, a slidably adjustable contact at the handle end of the rod and a second contact at its curved end respectively adapted to co-operate with a pair of fixed contacts on said base connected to the terminals of the electric supply, the fixed contact co-acting with the handle contact of the rod forming the rest for the work to be spotwelded and the other fixed contact forming the fulcrum upon which the rod turns during its movement to the spot welding position.

8. Electric spot welding apparatus comprising an insulated base, a metal plate mounted on said base provided with openings therein in register with alternative terminals of one polarity of the electric supply, a plug adapted to connect said metal plate with one or other of said terminals according to the voltage required, a fixed contact on said plate, a toggle lever system mounted on said plate, a cross head fitted at the free end of said toggle lever system, a fixed contact on said base connected to the terminal of the other polarity of the electric supply, a manually movable rod with a downwardly curved free end mounted in said cross head and adapted to be slidably adjusted therein in relation to the toggle lever system, a handle at the straight end of said rod, a slidably adjustable contact at the handle end of said rod and a second contact at its curved end respectively adapted to co-operate with said fixed contacts on the base and plate, the fixed contact on the base forming the rest for the work to be spotwelded and the fixed contact on the plate forming the fulcrum upon which the contact at the curved end of the rod turns during the movement of the contact at the handle end of the rod to the spotwelding position.

9. Electric spot welding apparatus comprising an insulated base forming the cover plate of a battery a metal plate mounted on said base provided with openings therein in register with alternative terminals of one polarity of the battery, a plug adapted to connect said metal plate with one or the other of said terminals according to the voltage required, a fixed contact on said plate, a manually movable rod mounted on said metal plate, means for restraining the movement of said rod to a predetermined path and a pair of contacts on said rod respectively adapted to co-operate with the fixed contact on said plate and a fixed contact on said base connected to the terminal of the other polarity of the battery and one of said fixed contacts forming the rest for the work to be spotwelded and the other forming the fulcrum upon which

said rod turns during its movement to the spot welding position.

10. Electric spot welding apparatus comprising an insulated base forming the cover plate of a battery, a metal plate mounted on said base provided with openings therein in register with alternative terminals of one polarity of the battery, a plug adapted to connect said metal plate with one or the other of said terminals according to the voltage required, a fixed contact on said plate, a toggle lever system mounted on said plate, a cross head fitted at the free end of said toggle lever system, a fixed contact on said base connected to the terminal of the other polarity of the battery, a manually movable rod with a downwardly curved free end mounted in said cross head and adapted to be slidably adjusted therein in relation to the toggle lever system, a handle at the straight end of said rod, a slidably adjustable contact at the handle end of said rod and a second contact at its curved end respectively adapted to co-operate with said fixed contacts on the base and plate, the fixed contact on the base forming the rest for the work to be spotwelded and the fixed contact on the plate forming the fulcrum upon which the contact at the curved end of the rod turns during the movement of the contact at the handle end of the rod to the spotwelding position.

11. Electric spot welding apparatus comprising a base, a toggle lever system mounted on said base, a manually movable rod mounted at the free end of said toggle lever system, a pair of contacts on said rod respectively adapted to co-operate with a pair of fixed contacts on said base connected to the terminals of an electric supply and one of said fixed contacts forming the rest for the work to be spotwelded and the other forming the fulcrum upon which said rod turns during its movement to the spot welding position, and spring means in the pivotal connections between the arms of the toggle frame tending to lift the spot welding contact off the work to be spot welded resting thereon.

12. Electric spot-welding apparatus comprising a pivotal manually movable rod, a pair of contacts on said rod respectively arranged on each side of its pivotal point, one of said contacts being adapted in one position of the rod to make electrical connection with a source of electrical energy, and the other of said contacts being adapted in the same position of the rod to make electrical contact through the work to be welded with the same source of electrical energy to complete the circuit through the rod and the work.

13. Electric spot-welding apparatus comprising a pivotal movable rod, a pair of contacts on said rod respectively arranged on each side of its pivotal point, a pair of contacts

connected to the terminals of a source of electrical energy and adapted to coact with the contacts on the rod, and means for completing the electrical circuit by directly contacting one contact on the rod with the corresponding contact on the terminal and indirectly

contacting the other contact on the rod with its corresponding contact on the terminal through the work to be welded.

In testimony whereof I have signed my name to this specification.

ROBERT DAVIDSON BELL.
